UNITED STATES PATENT OFFICE

2,278,104

WIRE FABRIC DEVICE

Noah S. Harter, Waukegan, Ill., assignor to The American Steel and Wire Company of New Jersey, a corporation of New Jersey

Original application October 13, 1938, Serial No. 234,853. Divided and this application November 22, 1940, Serial No. 366,759

1 Claim. (Cl. 219—4)

The present invention relates to a welding device suitable for operating on wire fabrics of the type shown in United States Patent No. 2,024,796, issued to me on December 17, 1935. The present application constitutes a division of my copending application Serial 234,853, filed October 13, 1938, entitled "Hardware and screen cloth machine."

As is set forth in the above identified copending application, the machine to which the present invention appertains is of the kind properly characterized as a loom in which warp wires and weft wires are advanced into interwoven association, and the latter are then trimmed, formed, and welded, into the proper selvage configuration. The present invention is primarily concerned with the welding instrumentalities participating in this selvage operation.

Since the general organization of my improved loom, together with its mode of operation, is completely set forth in the above identified parent application, no complete description thereof will be given herein and only such portions of the specification thereof will be set forth as is necessary for a thorough understanding of the welding devices comprising the subject matter of this divisional application, as is set forth in the appended claim.

The accompanying drawings showing Figures 1 to 5, inclusive, which correspond, respectively, to Figures 14, 15, 16, 19 and 20, of the aforesaid parent application, are described as follows:

Figure 1 shows a detailed top plan view of one unit (the right-hand unit) for shearing, bending and welding weft wires to form the selvage on the fabric being acted upon.

Figure 2 shows a side elevational view of the unit shown in Figure 1.

Figure 3 is a sectional view taken along line III—III in Figure 2.

Figure 4 is a view taken along line IV—IV in Figure 2.

Figure 5 is a schematic plan view showing a fragmentary portion of the finished fabric, and the various steps comprising its process of manufacture, including its formation and subsequent evolution.

Referring now to the detail views of Figures 1 to 5, inclusive, there is pictured the unit for completing the selvage of the fabric that is disposed at the right-hand side of the machine. This unit has been adopted for descriptive purposes since it is typical of the construction of both units, but has, in addition, a cutter for trimming the weft picket ends, which, on the left-hand unit,

by virtue of the shearing action between the reed and stationary weft guide, is not necessary. However, with this one exception, the two units are identical; it being understood, of course, that the elements of the left-hand unit are turned around to function in the opposite direction from those of the right-hand unit, illustrated in these figures.

Referring to Figure 5, it will be seen that the weft wires P leave the beater frame trimmed evenly on the left-hand side of the fabric, which is at the top of Figure 5, and somewhat raggedy at the right-hand side of the fabric, having been slightly overfed by pinch rolls (not shown) to insure that a sufficient amount is provided to form the selvage. The web is advanced between electrodes 88, two of which are respectively mounted over each of the outermost warp wires or selvage wires at each side of the fabric, and the other two of which are disposed in corresponding positions beneath the web. Thus is constituted the electrode jaws, the right-hand set of which appears in Figures 2 and 3, which are arranged for intermittent closing and opening motion in the vertical plane of the outermost warp wire.

In this connection it will be noted that the outermost warp wire lays on top of all weft wires rather than being interwoven therein, as is the case of the intermediate wires. This is to make both selvages uniform and to provide a continuous shoulder, equal in height to the diameter of the constituent wires, against which the exposed end portions of the weft pickets can be disposed after formation, so that no sharp ends will be left exposed. It will be apparent that the selvage warp wires are arranged wholly on one side of the fabric, in the manner described, by simply bypassing them through the heddles, whereby they are not deflected from their horizontal plane of feed, as is required to effect interweaving.

After the warp selvages have been welded so as to tack the opposite marginal portions of the web together, and to anchor the intermediate wires into place, the web is then passed on to the forming devices. First, however, it is necessary for the weft picket ends at the right-hand side of the fabric to be cut off evenly so as to correspond to their opposite ends at the left-hand side of the fabric. It has already been indicated that this is only necessary at the right-hand side of the machine, and is effected by a shear 89, as is schematically represented in Figure 5.

The web then passes by the first forming tools 90 whereby each end of each picket wire is simultaneously crimped, as shown in Figure 5. Thereafter, crimped weft pickets are bent into final position, as at 91, as is also shown in Figure 5, after which they are finally welded as at 92, and passed on to the take-up. The instrumentalities for thus treating the selvages of the fabric will now be described in greater detail, reference being first made to Figures 1 and 2.

The first instrumentality, in the order in which the web is presented, is the warp selvage welder 88 shown in Figures 1, 2 and 3, as comprising a mounting 98 with four bearings 99 in which a pair of shafts 100-101 are mounted so as to extend transversely of the machine. The shafts are spaced an equal distance above and below, respectively, the plane of the fabric to which they are substantially parallel. Since the precise thickness of the material to be welded, which must pass between the electrodes 88, is indeterminable in advance, and may vary somewhat through any operating period, it is necessary for the positive cam action by which these electrodes are operated, to be applied in such a manner as to compensate for these variables.

To this end, adjacent to the outer extremity of each of the shafts is a free running collar 102, within which the shaft may rotate, and to which may be imparted rotary or oscillatory motion independently of the shaft. Immediately adjacent the free running collar on each shaft is another collar 103 which is keyed to the latter so as to have no motion independently thereof. The free running collar is provided with a horizontally-extending radial lug 104 on the end of which is provided a roller 105 for engagement with an actuating cam 106 carried on the cam shaft 95. The keyed collar 103 on each shaft is provided with a spring bearing extension 107, a portion of which overlies the free running collar 102. The near face of the radial lug 104 on the free running collar is arranged in substantial parallelism with the spring bearing extension 107 of the keyed collar, with which it aligns circumferentially of the shaft 100-101. Between these parallel portions of the adjacent collars is disposed a compression spring 108 which transmits the motion of the cam 106 from the free running collar 102 to the keyed collar 103, and hence to the shaft 100-101 on which the latter is secured. From the foregoing it will be seen that should anything prevent the shafts from rotating to the extent required by the cam, as would be the case if an unusually large wire or obstruction on the wire came between the electrodes 88, the compression spring 108 would insure the movement of the shaft to close the electrodes as far as possible, but would thereafter yield to provide lost-motion, and thus to compensate for the shaft's inability to rotate the full amount.

Each of the shafts is provided at its inner end with another non-rotative collar 109 to which a tangential extension 110 is rigidly affixed. The outer end of each tangential extension is provided with a contactor element 111 of the electrode, both of which are arranged in vertical alignment relative to each other. As the web advances, successive intersections between the warp selvage and picket wires are disposed between the electrodes, which are then moved by the cam mechanism, described above, into engagement with the wires at each side of the intersection thereof, to effect the weld. The weld-

ing circuit (not shown) is completed through the intersection of the wires by one side of the circuit being introduced through one of the electrodes, and by the other side of the circuit being introduced through the other electrode. The electrodes are preferably energized directly through the tangential extension and associated parts, which are usually formed of conductive metal, from which other parts of the machine are electrically isolated by insulative washers and bushings of any suitable form.

During the welding operation, the portions of the wires through which the current passes become red-hot, in which condition the ends of the picket wires are frequently subject to bending under their own weight. In order to preclude this happening, the tangential extension 110 of each electrode has secured to it on a face opposite to that of the contactor element 111, so as to extend parallel to the latter, a support guide 112 which is adapted to give the picket ends the requisite support during the application of the welding current in order to obviate the "wilting" of the latter. Since these support guides are usually of metal, care should be taken to provide for their being suitably insulated from the tangential extensions upon which they are respectively carried, as is shown in Figure 1.

To insure that the electrodes return to open position after a weld has been effected, a small spring 113 is provided to lift the upper electrode, as is shown in Figure 2, and a similar spring may be provided to control the lower electrode, although none has been illustrated because it has been found that this electrode will return by gravity during a recession of the cam 106.

After the warp selvages have been welded, as last described, the web advances to a shearing mechanism 89 which acts to trim, evenly, the ends of the weft pickets extending from the right-hand side of the web (see 89, Figure 5).

The web then proceeds to the crimping and bending tools shown at 90 and 91 in Figure 5. As will be understood from the complete description thereof contained in my parent application, these comprise a unitary compound tool which works simultaneously upon adjacent pickets to form the selvage.

After the picket wires have been formed into the selvage configuration in the manner shown in Figure 5, the fabric passes on to the final welders 92, the right-hand one of which is shown in Figures 1, 2 and 4. By this mechanism the crimp of one wire is welded to the bend of an adjacent wire to complete the fabric.

With reference to the enlarged detail view of Figure 4, it will be seen that each of these welders comprises a base 151 adapted for mounting on the dove-tail bearing 94, referred to hereinbefore, on which base is mounted a pair of upstanding pivot bearings 152, in which a pair of scissors-like rocker beams 153-154 is pivoted by means of a pin 155 that is secured in the bearings 152 in any suitable manner. To the inner extremity of each beam is secured an electrode mounting 156 in which an electrode 157 is adapted to be held for axial adjustment by means of nuts 158. The nuts, with the aid of washers 159, support the electrode in an enlarged opening 160 in the mounting 156, within which, by loosening the nuts, the electrode may be moved axially of the mounting to effect a refinement of adjustment in accurately locating the weld with relation to the parts to be welded. It will be apparent that longer or shorter electrode mountings 156 may

replace the ones in use at any given time by removing the screws 161 and making the required substitution to provide for any change in the welding location, or to permit more than one joint to be welded transversely of the fabric.

The opposite extremity of the scissors-like beams 153—154 are provided with cam engaging rollers 162 through which movement of the cam 163 is transmitted to open and close the electrodes 157 to permit the passage and effect the welding of the selvage edges of the fabric. Here again it becomes necessary to compensate for variations in the thickness of the material passing between the electrodes so that, when the latter are obstructed against closing the predetermined amount, the positive action of the cam is harmlessly dissipated through lost motion means.

To accomplish this, the upper rocker beam 153 is made in two parts, the inner end 153a of which supports the electrode, and the outer end 153b of which engages the cam; both parts being pivoted on the pin 155. Each of these parts adjacent the pin is provided with an upstanding extension 164a and 164b, one of which (164b) is longer than the other, and which is formed over and downwardly as at 165 to lie over and around the adjacent extension 164a, as is shown in Figure 4. Between the two extensions a compression spring 166 is arranged, the expansive force of which may be varied by the set screw 167 and lock nut 168. By means of this spring, the cam action is yieldingly transmitted to the upper electrode. The overhanging portion 165 of the extension 164b is provided to insure that the upper electrode is returned to the open position simultaneously with the lower electrode during the recession of the cam, which opening is facilitated by means of another compression spring 169 disposed to draw the cam extremities of the scissors-like beams together.

As in the case of the first welders 88, described above, the welding current is applied to the final welders 92 through the elemental parts thereof which are made of conductive material. One

side of the circuit is supplied to the lower electrode, and the other side of the circuit is supplied to the other electrode. The two are isolated from each other and from contiguous parts of the machine by suitable insulatory bushings, washers, etc., in a manner well known in the electrical arts.

Many changes may be made in the structure and operating characteristics of the preferred inventive embodiments herein illustrated, which, though departing from the letter of this specification and drawings, will not depart from the spirit of the invention as apprehended in and by the following claim. It is intended, therefore, that the invention herein set forth be limited only by the claim construed in the light of this specification and drawings, and the prior art, and not be deemed limited to the specific embodiments here adopted as preferential for purposes of description.

I claim:

In a selvaging device: a welding tool comprising a pair of horizontally journaled, parallel shafts; a tangential extension carried by each shaft so that the terminal portions of each extension aligns in the vertical with the other thereof; a collar fixed to each shaft; a free-running collar disposed adjacent each fixed collar; a lug on each fixed collar extending into alignment with a lug on each free-running collar circumferentially of their respective shafts; a compression spring disposed between the lugs of adjacent collars on the same shaft, a stud projecting from each free-running collar carrying a roller, and a cam coacting with said rollers effective to rock said free-running collars, the assemblage being so coordinated that the motion imparted by the cam is transmitted through said springs to said fixed collars and thence to said shafts, whereby compensation is automatically made for variations in the thickness of material acted upon by the said extensions.

NOAH S. HARTER.
